RAILWAY BRAKE BEAM STRUCTURE

Thomas C. Soddy, Chicago, Ill., assignor to Chicago Railway Equipment Company, Chicago, Ill., a corporation of Illinois

Filed Jan. 24, 1957, Ser. No. 636,182

6 Claims. (Cl. 188—207)

The invention relates to railway rolling stock brake beams and their support from associated truck structure.

One object of the invention is to support a brake beam in close relation to a truck frame part immediately above the beam so that the beam may have the swinging movement provided by the usual elongated hanger suspended from the truck frame.

Another object is to adapt a brake beam end member for support by a swing hanger positioned at the rear of the beam without interfering with a desirable mounting of the head on the beam involving the presence of a rivet extending forwardly and rearwardly of the head, diagonally of the length of the beam.

Another object is to arrange the end member of a brake beam, which pivotally mounts a separate head, so that the end member and adjacent main elongated part of the beam may be secured together by a rivet extending diagonally forwardly and rearwardly of the brake head.

These and other detail objects are attained by the structure illustrated in the accompanying drawings, in which:

Figure 1 is in part a top view and in part a horizontal section through a beam embodying the invention, a portion of the beam being broken away to show the parts on a larger scale.

Figure 2 is an elevation of an end of the beam with adjacent truck parts also shown.

Figure 3 is a top view of the beam end member with the rotatable adjustable head removed.

Figure 4 is a detail transverse section on line 4—4 of Figure 3.

Figure 5 is a detail top view of one end of another form of beam embodying the invention.

The beam is of a truss type embodying a compression member 1 of channel section, a tension member 2 of rectangular bar section, a strut 3 holding the intermediate portion of the compression and tension member apart, end members 4 riveted at 5 to the converged end portions of the compression and tension members. End member 4 includes a body portion having a cylindrical periphery 6. A brake head 7 is rotatably mounted on each end member cylindrical portion. A spring pressed pawl 8 is seated in each brake head and engages a ratchet 9 in the end member, whereby the head is held in an angular position upon the sleeve determined by the application of the brake to the truck wheels. The head is provided with forwardly facing shoe mounting elements 10 for supporting the renewable shoe 11.

All the above described structure is conventional. It is common practice to support the brake beam from lateral brackets on the truck side frames by elongated swing hangers, the lower ends of which pass through or are pivotally bolted to the head body immediately at the rear of the shoe-mounting elements. The present beam support is adapted for mounting the beam on a truck frame having parts indicated at 15 and 16 extending transversely of the truck immediately over the brake beam and therefore making it impractical to suspend the beam in the usual manner. To meet this condition, the head

2

mounting end member 4 is provided with a bracket 17, 18 (Figure 3) projecting laterally from the head-mounting periphery 6 and rearwardly from the rear face of compression member 1 (Figure 1). A horizontal passage through bracket lug 18 receives a bolt 19 by which the beam is pivotally connected to the bifurcated lower end of an elongated hanger 20 (Figure 2) supported from a bracket 21 projecting rearwardly of the beam from truck frame member 15.

10 The rivet 5 which secures sleeve 4 to the compression and tension members is disposed diagonally of the compression member and substantially at right angles to the main portion of the tension member. Its heads grip correspondingly inclined surfaces on the sleeve, the forward surface being on a flange-like projection 6a on the sleeve projecting laterally outwardly from the head mounting periphery, the rear surface being on a portion of the sleeve similarly inclined and forming a recess 22 in the cylindrical periphery 6 whereby the rivet head is received within the circular periphery of the brake head. Preferably, an additional rivet 23 is applied to a flange 24 on bracket 17 and to the adjacent portion of the compression member.

With this arrangement the beam may swing to and from the wheels about the usual radius irrespective of the close approach of the truck frame to the brake beam and to the wheels.

25 The end member 4 may be interchanged with a brake head mounting end member which involves the suspension of the brake beam from the adjacent framing by a link connected directly to the brake head.

30 Figure 5 illustrates another form of the invention in which a cast metal beam includes a compression member 31 and a tension member 32 merging at their ends in a cylindrical mounting 35 for a self-adjusting brake head 36. A hanger-engaging bracket 37 is integral with the end portion of the beam and projects rearwardly from compression member 31, being offset inboard of the beam from the brake head and its mounting elements.

35 40 This one-piece casting arrangement provides a rigid structure and avoids rivets, keys, wedges or other attaching elements. The beam would be supported by swing hangers, as indicated at 20 in Figure 2.

45 The details of the invention may be varied otherwise than as shown without departing from the spirit of the invention and the exclusive use of those modifications coming within the scope of the claims is contemplated.

What is claimed is:

1. A railway truss brake beam structure comprising 50 compression and tension members, converging from the middle of the beam towards the ends of the beam, there being rigid unitary structure at each end of the beam comprising a member for mounting a brake head and provided with a projection extending transversely of the beam and offset from the end of the beam lengthwise thereof inboard from the brake head mounting and including a hanger-receiving part spaced rearwardly from the compression member.

55 2. A railway brake beam including compression and tension members converging from the middle of the beam towards the ends of the beam, the ends of said members extending alongside each other, there being an end member at each end of the beam with a body portion surrounding the ends of the compression and tension members and seated thereon and holding them assembled and adapted to mount a brake head, and a bracket on said portion extending therefrom inboard of the beam and having a bearing rearwardly of the beam compression member for a hanger-engaging pivot bolt.

60 65 70 3. A railway brake beam including compression and tension members converging from the middle of the beam towards the ends of the beam, the ends of said

members extending alongside each other, there being an end member at each end of the beam with a sleeve-like body portion surrounding the ends of the compression and tension members and seated thereon, a brake head rotatably mounted on said end member, there being a bracket on the rear of said end member extending in-board from said body portion and provided with a hanger-receiving lug offset rearwardly of the compression member, and a rivet extending through said compression and tension members and diametrically through the part of said sleeve-like body portion nearest the end of the beam.

4. A railway brake beam according to claim 3 in which the rivet is inclined to the length of the beam and the periphery of the end member is recessed to accommodate the rear head of the rivet between the sides of the brake head.

5. A railway brake beam end member constructed and arranged to mount an adjustable brake head and comprising a body part with a cylindrical seat for the brake head and provided with an axial passage for receiving the ends of a truss type brake beam compression and tension member, there being a lateral extension on said

body at one side of said seat and disaligned with said seat lengthwise of the beam and provided with an opening for receiving a brake beam hanger inboard of the brake beam head.

6. A railway truss type brake beam end lock member having a brake head mounting body portion and having a rearwardly extending hanger-engaging part offset in-board from the head mounting body portion.
